UNITED STATES PATENT OFFICE

FEDERICO TROCCOLI, OF BOSTON, MASSACHUSETTS

HAIR-DRYING DEVICE

Application filed February 3, 1928. Serial No. 251,544.

This invention relates to improvements in hair drying devices and one of the objects of the invention is to provide means for drying the hair upon the head of a person rapidly and evenly.

I am aware that various devices for drying the hair have heretofore been employed, including fans for delivering a blast of air upon the head, hose or other conduits for conducting a blast of heated air upon the head, and devices in the nature of a helmet, adapted to enclose the upper portion of the head of the person, having an interior shell through apertures in which air is projected upon the head of the person. Fans and hose are capable of projecting the air only upon a portion of the head of the person, while helmet devices confine the air about the head, and if the air is heated are exceedingly uncomfortable to the person.

A further object of the invention is to provide a hair drying device which will project a plurality of unconfined blasts of, preferably heated, air upon such different portions of the head of the person as will rapidly and evenly dry the hair.

A further object of the invention is to provide the respective air delivery devices with distributing means which will divert the air delivered from the air delivery devices in such a manner that practically all of the hair of the head will be dried simultaneously.

A further object of the invention is to provide adjustable air distributing devices which will enable them to be located at different distances from the head of the person and which also desirably are so constructed as to permit the respective blasts of air to be projected in such different directions as may be necessary or desirable.

A further object of the invention is to provide a device of the character described with convenient mechanism for heating the air which is delivered from the air delivering means.

These and other objects and features of the invention will more fully appear from the following description and the accompanying drawing and will be particularly pointed out in the claims.

A preferred embodiment of the invention is illustrated in the accompanying drawing, in which,

Fig. 1 is a side elevation of the hair drying device assembled upon suitable means for supplying air under pressure thereto and also with means for heating the air;

Fig. 2 is a detail front elevation of the hair drying device;

Fig. 3 is a detail vertical sectional view of the central air delivering branch or nozzle;

Fig. 4 is a detail plan view of the hair drying device illustrating in dotted lines the manner in which the air is projected from the air delivering means upon the head of a person;

Fig. 5 is a detail longitudinal sectional view of one of the branch conduits and an air delivery device adjustably mounted thereon; and,

Fig. 6 is a detail view of the end and mouth of the air delivering means shown in Fig. 5.

The assembled hair drying mechanism illustrated in Fig. 1 comprises a hair drying device having an inlet conduit 1, which is connected at one end to, and preferably telescopically mounted upon, the delivery pipe 2 of a blower 3 adapted to supply air under pressure to the hair drying device. By reason of this construction the blower may be mounted upon a portable base and the conduit 1 vertically adjusted upon the delivery pipe of the blower so that the hair drying device may be located at such distance from the floor as may be required to position the hair drying device properly with respect to the head of the person seated in a chair.

Suitable means may be provided for heating the air which is supplied to the hair drying device and this, as illustrated in Fig. 1, comprises an electrically heated coil 4 which is located within the delivery pipe 2. Obviously other usual means may be employed for heating the air.

In the construction illustrated in Fig. 1 the blower 3 is mounted upon a suitable pedestal or base 5 which constitutes a convenient mounting where the device is to be used in a

hairdressing parlor or a barber shop. Obviously the device may be portable.

Where the device is used in barber shops or hairdressing parlors having means for supplying a conduit with heated or unheated air under pressure, the hair drying device embodying the invention may be suitably attached to such conduit. In the preferred form of hair drying device illustrated in the drawing the inlet conduit 1 thereof communicates with a plurality of branches arranged respectively to deliver the air upon the back and sides of the head of a person. The central branch comprises a conduit 6 provided with an air delivery nozzle 7 which desirably is telescopically and rotatably mounted upon the branch 6 and is provided at its end with a preferably conoidal deflector 8 of considerably less diameter than the diameter of the nozzle 7 and which preferably extends at an angle to the axis of the nozzle 7. By reason of this construction a portion of the air which is projected through the nozzle 7 will be diverted upwardly through the deflector 8 along and over the top of the head, while the remainder, and larger portion, of the air will be projected upon the back of the head and downwardly along the neck of the person. By rotatably adjusting this device about its axis, however, the nozzle 8 may be positioned to project the air further down upon the neck of the person. By slidably moving the nozzle 7 the mouth thereof may be placed at a greater or less distance from the head of the person so that a desirable distribution and strength of blast may be provided.

The other branch members, which diverge from the central branch 6 and which desirably lie in substantially the same plane therewith, may be identical and comprise conduits 9 and 10 which communicate at one end with the conduit 1 and may be properly curved at their delivery ends to project suitable blasts of air upon the side of the person's head which is located in front of the central nozzle 6. Desirably the air delivering branches 9 and 10 are provided with adjustable air delivery members which are so formed and arranged as to project the air upon the head in the manner aforesaid. As illustrated herein the air delivery members comprise tubes 11 and 12 which are telescopically mounted upon the branches 9 and 10 and are also rotatably adjustable relatively thereto. The ends of these air delivery devices are curved toward each other and present mouths 13 and 14 lying in parallel planes upon opposite sides of the position of the head of the person. By moving the air delivery members longitudinally upon the branches 9 and 10, the position of the mouths 13 and 14 may be separated to greater or less distances, thus modifying the strength of the blast projected therefrom by reason of the greater distance from the head. Furthermore, such adjustment permits the head to

be moved toward or from the position of the nozzle 7. As the nozzle 7 is also adjustable the position of the several air delivery devices may be so adjusted as to produce a substantially uniform rate of drying of the hair.

The mouths 13 and 14 of the air distributing devices desirably are provided with deflectors 15 which, in the form illustrated in Figs. 5 and 6, are curved and extend transversely across and in angular relation to the axes of the mouths 13 and 14. These deflectors serve to project a portion of the air toward the rear of the head, as illustrated in dotted lines in Fig. 4, while the main portion of the air is projected upon the side and forward portion of the head.

The air delivery members 11 and 12 preferably are also capable of rotation upon the branches 9 and 10 respectively so that the direction in which the blast of air is projected upon the head may be varied vertically as may be required or desired.

By reason of the construction above described the blasts of air which are projected upon the head of the person are unconfined so that the moisture which is absorbed from the hair is rapidly dissipated throughout the room. The mechanisms for delivering air upon the head are such that a substantially even distribution is made over the entire head and the hair dried quickly and uniformly. If, by improper positioning of the head relatively to the hair drying device, or by variations in thickness of the hair, some portion dries more slowly than others, the delivering members may be so adjusted as to project the blast directly upon such more moist portion so that it will be dried rapidly. By reason of the divergence of the branches 9 and 10, the mouths 13 and 14 of the air delivery members 11 and 12 may be located at such convenient distances from the side of the head of the person as to insure the comfort of the person, both with respect to the strength of the blast, and with respect to the heat of the air which is projected upon the head.

While the apparatus illustrated in the accompanying drawing is of the type adapted to be employed in hairdressing parlors, barber shops, and the like, it is obvious that the hair drying device embodying the present invention may be employed for household use, and the air under pressure supplied from such blower as may be present in the household such as the blower of a vacuum cleaner, many types of which commonly in use have hose attachments through which a blast of air is projected. In such case the air may be taken from proximity to a radiator or register, or suitable electrical or other heating means to heat the air within the hose or within the conduit leading to the air delivery members.

It will be understood that the particular

embodiment of the invention disclosed herein is of an illustrative character and is not restrictive, and that various changes in form, construction and arrangement of parts may be made within the meaning and scope of the following claims.

Having thus described the invention, what is claimed as new, and desired to be secured by Letters Patent, is:

1. A hair drying device comprising a conduit to receive air under pressure having a plurality of air delivery branches lying in substantially the same axial plane arranged respectively to project blasts of air upon the back and opposite sides of a person's head and means in the respective side branches for distributing the air projected therefrom, and means for causing the blast upon the back of the head to pass both downwardly along the neck and upwardly along the top of the head.

2. A hair drying device comprising a conduit to receive air under pressure having air distributing branches having their ends arranged to project unconfined blasts of air upon opposite sides of a person's head, and a nozzle to project a blast of air upon the back of the head provided with means for deflecting a portion of the air delivered therefrom in an angular direction with respect to the axis of the mouth of said nozzle.

3. A hair drying device comprising a conduit to receive air under pressure having air distributing branches having their ends arranged to project unconfined blasts of air upon opposite sides of a person's head, a nozzle to project a blast of air upon the back of the head provided with means for deflecting a portion of the air delivered therefrom in an angular direction with respect to the axis of the mouth of said nozzle, and means for adjusting said nozzle whereby the diverted portion of said blast of air may be projected upwardly along the top of the head or downwardly along the neck of the person.

In testimony whereof, I have signed my name to this specification.

FEDERICO TROCCOLI.
